UNITED STATES PATENT OFFICE.

WILLIAM KLOCHE, OF BROOKLYN, NEW YORK, ASSIGNOR TO E. W. BLISS COMPANY, OF BROOKLYN, NEW YORK, A CORPORATION OF WEST VIRGINIA.

ADJUSTABLE-STROKE PRESS.

1,258,020.

Specification of Letters Patent. Patented Mar. 5, 1918.

Application filed February 10, 1917. Serial No. 147,742.

To all whom it may concern:

Be it known that I, WILLIAM KLOCHE, a citizen of the United States of America, residing in the borough of Brooklyn, county 5 of Kings, in the city and State of New York, have invented certain new and useful Improvements in Adjustable-Stroke Presses, of which the following is a specification.

My invention relates to a press, and is 10 particularly adapted to a press or other machine of this type wherein rotary motion from a shaft is communicated to a longitudinally reciprocating member by means of a crank and pitman, and has for its object 15 to provide a simple and easy adjustment of the stroke of the pitman by means of a change in its effective or working length. To this end my invention consists in introducing between the pitman and crank an adjusting connection such as a bushing, which 20 is revoluble in position and is eccentric to the crank, and which, when adjusted so as to bring its eccentric portion at varying places between the pitman and crank, will 25 thereby vary the effective length of the pitman and accordingly will vary its stroke.

My invention also contemplates the provision of means for holding or locking the adjusting means in adjusted position. A 30 desirable form in which my invention may be embodied is illustrated in the accompanying drawing, wherein,—

Figure 1 illustrates an elevation, partly in section, of a portion of the upper end of a 35 drawing press illustrating the application of my invention;

Fig. 2 is a detail of part of the structure shown in Fig. 1, illustrating a locking key in place;

40 Figs. 3, 4 and 5 are cross-sections on these respective lines of Fig. 1;

Fig. 6 is a detail view of the adjusting member or bushing, and

45 Fig. 7 is a detail view of the locking key, which is shown in place in Fig. 2.

My invention is illustrated as applied to a simple type of press such as a drawing press, and it is extremely useful in connection with such type of machine, but its 50 utility is not confined to a press, as it is equally available for use in any type of machine employing a crank and pitman where it is desired to vary the stroke of the pitman.

55 The particular type of machine in connec-

tion with which I have illustrated my invention has a driving shaft A provided with a crank B from which the rotary motion of the shaft is communicated to the longitudinally reciprocating pitman C. The pitman 60 has the usual head X for receiving the crank B provided with a separable yoke D, and my invention of means for varying the stroke of the piston is located in the head and interposed between the same and the crank. 65 As shown, the adjusting means comprise a sleeve or bushing E which is revolvably mounted in an annular opening in the head X, and which is perforated at F for the passage of the crank B. As will be clearly apparent from the section Fig. 5, the center of the bushing E is eccentric to the axial center of the crank B. Therefore, when it is desired to vary the effective length of the pitman C this may be accomplished by rotating 70 the bushing E in the head X, whereby the pitman C may be either raised or lowered on the crank, as desired.

For the purpose of holding the bushing in 75 adjusted position, I provide the same with the axially extending flanges G, H, which are located one on each side of the said bushing and enter corresponding axially arranged channels I, J in hubs K, L on the shaft. The said flanges G, H are respectively provided with notches or recesses g, g¹, g², g³, there being as many such notches as it is desired there shall be adjustments provided for the pitman. The notches in the respective flanges are alike. Only flange 80 G is illustrated, but flange H will have corresponding notches and the notches will be located a distance apart corresponding to the extent of adjustment desired. The notches coöperate with a key M upon a removable bracket N for the purpose of holding the bushing E in adjusted position. This is accomplished by turning the bushing in the head X until a pair of the notches appear in front or at the left, as indicated 85 in Fig. 3, where the hubs K, L are cut away so that the flanges G, H emerge from their channels I, J. Thereupon the brackets N, of which two are provided, are applied, so that their respective keys M will enter the 90 recesses in the flanges, and the brackets may then be secured in position by suitable means such as the bolts n illustrated.

For the purpose of facilitating the turning of the bushing E the peripheral flanges 110

e of the same are provided with a series of notches O which may be engaged by a spanner wrench to turn the said bushing.

It will be perceived that by the use of my invention the desired shortening or lengthening of the stroke of the pitman may be accomplished in a simple and expeditious manner. It is only necessary to remove the two brackets N and then to apply a spanner wrench to the bushing E and turn the same until the notches indicating the desired adjustment appear at the front of the machine, and thereupon the brackets N may be replaced with the keys M entering these said notches. The bolts n being then applied, the brackets will be secured in position and the bushing will be securely held relative to the shaft and the pitman will freely turn thereon.

For the purpose of assembling the parts I prefer to split either the driving member or the driven member. As illustrated, the shaft A is split at one side of the crank by being divided transversely on the line P. A stub Q on the end of the shaft enters an axial channel R at the other side of the split, and these parts are eccentrically located relative to the axis of the shaft so as to cause the two parts to turn together. A taper pin Y passes through the shaft A and stub Q and provides means for locking the two parts of the shaft together.

Each bracket is provided with a central backing-out screw bolt S which is screwed through the bracket to back the same out of locking position. The bolt S on the left-hand side engages against the pin Y and holds the same firmly in position. On the other side the bolt S engages against the shaft.

I have illustrated in the accompanying drawings, and have described, the most desirable manner of constructing my invention now known to me, but it will be apparent to those skilled in the art that the same may be otherwise constructed than as illustrated, and that numerous modifications and differing embodiments thereof may be produced within the limits of the appended 50 claims.

I claim as my invention:—

1. In a press, a crank, a pitman, an adjustable eccentric bushing between said parts, and a lock for locking said bushing in adjusted position fixed with relation to the crank, said lock acting to resist turning movement of the bushing on the crank equally in both directions.

2. In a press, a split shaft, a crank adjacent the split, an eccentric bushing on the crank and adjustable in position thereon and normally fixed with relation thereto.

3. In a press, a driving member comprising a shaft having a crank thereon, a driven member comprising a pitman having an

annular opening for said crank, and a bushing revolvably mounted in said opening and adapted to surround said crank, said bushing being eccentric to and normally fixed with relation to said crank and adjustable in position to vary the stroke of the pitman, and one of said driving and driven members being split to assemble the parts.

4. In a press, a split shaft, a crank adjacent the split, a pitman connected to the crank and an eccentric bushing between the parts and adjustable in position to vary the stroke of the pitman, said bushing being normally fixed with relation to said crank.

5. In a press, a split shaft, a crank adjacent the split, a pitman connected to the crank and an eccentric bushing between the parts and adjustable in position to vary the stroke of the pitman, and means for locking the bushing in adjusted position, and normally fixed with relation to said crank.

6. In a press, a shaft, a crank thereon, a pitman driven from said crank, means for adjusting the stroke of the pitman comprising a revoluble bushing in the pitman, and means for locking said bushing in adjusted position comprising an annular flange in the bushing adapted to enter a corresponding groove in the shaft, said flange having notches corresponding to the number of adjustments desired, and a bracket detachably attached to said shaft and having a key adapted to enter a notch in the flange.

7. In a press, a split shaft, a crank thereon adjacent said split, a pitman driven from said crank and means for adjusting the stroke of the pitman comprising a revoluble bushing in the pitman, and means for locking said bushing in adjusted position comprising an annular flange in the bushing adapted to enter a corresponding groove in the shaft, said flange having notches corresponding to the number of adjustments desired, and a bracket detachably attached to said shaft and having a key adapted to enter a notch in the flange.

8. In a press, a split shaft, a crank thereon adjacent said split, a pitman driven from said crank, means for adjusting the stroke of the pitman comprising a revoluble bushing in the pitman, and means for locking said bushing in adjusted position comprising an annular flange in the bushing adapted to enter a corresponding groove in the shaft, said flange having notches corresponding to the number of adjustments desired, and a bracket detachably attached to said shaft and having a key adapted to enter a notch in the flange, and said locking means being duplicated on each side of said crank.

9. In a press, a shaft, an eccentric part fixed to said shaft, means for locking said eccentric part in fixed position, and a longitudinally reciprocating part actuated there-

by, said eccentric part being adjustable to vary the length of the stroke, and having its center of adjustment eccentric to the center of the shaft, and said locking means acting 5 to resist turning movement of said eccentric part equally in both directions.

10. In a press, a split shaft, an eccentric part fixed to said shaft and a longitudinally reciprocating part actuated thereby, said eccentric part being adjustable to vary the 10 length of the stroke, and having its center of adjustment eccentric to the center of the shaft.

11. In a press, a shaft, hubs thereon, an

eccentric part and interengaging means between said hubs and said eccentric part, fixing said eccentric part to said shaft, and a longitudinally reciprocating part actuated thereby, said eccentric being adjustable to vary the length of the stroke, and having its 20 center of engagement eccentric to the center of the shaft.

In witness whereof, I have hereunto signed my name.

WILLIAM KLOCKE.
